UNITED STATES PATENT OFFICE.

ARNOLD LAING, OF WINNIPEG, MANITOBA, CANADA.

MIXING DEVICE FOR INTERNAL-COMBUSTION ENGINES.

Application filed March 1, 1924. Serial No. 696,308.

To all whom it may concern:

Be it known that I, ARNOLD LAING, a subject of the King of Great Britain, and resident of the city of Winnipeg, in the Province of Manitoba, Canada, have invented certain new and useful Improvements in Mixing Devices for Internal-Combustion Engines, of which the following is the specification:

10 The invention relates to improvements in mixing devices particularly adapted for use on internal combustion engines, and an object of the invention is to provide a device which can be readily attached between the intake manifold and the carburetor of an internal combustion engine and will operate to effectively mix the fuel passing from the carburetor through the manifold to the engine cylinders and in so doing materially increase its efficiency in the engine cylinders.

15 A further object is to construct the device so that it can be inserted and fastened in place without altering the present construction of the manifolds and also to construct it so that the fan utilized can be easily removed for inspection or re-placement purposes.

20 A further object of the invention is to construct the device so that all the fuel passing to the intake manifold has to come under the action of the fan with the result that it is all effectively broken up prior to passing to the engine cylinders.

25 With the above more important objects in view the invention consists essentially in the arrangement and construction of parts hereinafter more particularly described, reference being had to the accompanying drawing in which:

30 Fig. 1 is a front view of the device as it appears when installed between the carburetor and the intake manifold of the engine.

35 Fig. 2 is an enlarged detailed horizontal sectional view at 2-2' Figure 1 and looking in the direction of the applied arrow.

40 Fig. 3 is a vertical sectional view at 3-3' Figure 2 and looking in the direction of the applied arrow.

45 Fig. 4 is a vertical sectional view at 4-4' Figure 3 and looking in the direction of the applied arrow.

50 Figure 5 is a perspective view of a fan detached from the casing of my device.

In the drawing like characters of reference indicate corresponding parts in the several figures.

The carburetor 1 which may be of any approved design, is provided with the customary attaching flange 2 whereby it is connected to the complementary flange 3 of the intake manifold 4. Under ordinary conditions the flanges 2 and 3 are placed face to face and fastened together by similar inner and outer bolts which pass through registering openings 5 and 6 provided in the flanges.

When my mixing device, which is indicated generally by the reference numeral 7, is installed on the engine, the carburetor is removed from the manifold to permit of the insertion of the mixing device which is provided with end flanges 8 and 9 complementary to those 2 and 3 and provided with pairs of openings 10 and 11 adapted to register with the pairs of openings 5 and 6 of the flanges 2 and 3. A pair of bolts 12 and 13 which are somewhat longer than those customarily employed, are then passed through the flanges and upon the nuts 14 of the bolts being tightened up, the vaporizer is securely fastened in place.

The body 15 of the mixing device carries the end flanges 8 and 9 and is shown in the present instance as substantially square or box-like in form and it is provided internally with a horizontally disposed, transversely extending, cylindrical chamber 16, the inner end being closed by the back or inner wall 17 of the body piece, whilst the forward or outer end is closed by a removable cover plate 18 demountably fastened in place by screws 19. Inlet and outlet openings 20 and 21 are located at the sides of the chamber, these communicating through the flanges 8 and 9 with the carburetor 1 and the intake manifold respectively and it will here be observed that the ends of the openings next the chamber are contracted and of an oval shape, whilst the outer ends are circular and are provided with seats for 100 gaskets 22 and 23.

The plate 18 carries a pin or spindle 24 which is permanently secured thereto and passes centrally through the chamber 16 and has the inner end thereof seated in a 105 suitable socket 25 formed in the back wall 17 of the body piece. On the spindle I mount rotatably a fan 26 which embodies

a sleeve-like hub 27 and extending lengthwise spiralling, equi-spaced blades or wings 28. The fan is of such a size that the outer tips of the blades make sliding contact with the 5 circular wall of the chamber 16 and the ends thereof make sliding contact with the ends of the said cylindrical chamber. In other words the fan fills the chamber, so to speak, but is free to rotate therein and 10 the firing mixture can accordingly only reach the manifold after it is passed through the fan in the pockets provided between the blades.

When the device is in use the suction of 15 the engine cylinders causes the fan to rotate at a high velocity and in rotating, the fan very effectively breaks up, and mixes the passing charge with the result that when it subsequently reaches the cylinders it is 20 highly efficient.

I am aware that fans have heretofore been used, such being horizontal fans and having their axis aligned with the direction of passage of the firing mixture. In such latter types of fans a certain proportion of the firing mixture can pass through the fan without being operated on thereby. In my case, however, the fan is positioned transversely of the direction of the firing mixture and is 25 so mounted that it positively obstructs the passage of the firing mixture so that it cannot get from the carburetor to the manifold without being positively brought under the influence of the rotating fan. In this way 30

all the firing mixture entering the intake 35 manifold is subjected to the action of the fan.

What I claim as my invention is:

A mixing device for internal combustion engines comprising a casing provided with a transverse chamber cylindrical in cross section and with aligned openings located at opposite sides of the chamber at points intermediate the length of the latter, said 40 openings being made flaring with the restricted ends communicating with said chamber, the lower wall portions of the openings being inclined at a steeper angle than the upper portions and in such manner that the inner lower portions of the openings 45 terminate at a level coinciding with the horizontal axis of the chamber, a longitudinal axially extending shaft mounted in said chamber, a sleeve rotatable on said shaft and extending the full length of the chamber and a plurality of spirally curved blades carries by the sleeve, certain of said blades 50 extending the full length of the sleeve and other of said blades being made of less length to extend from one end of the sleeve 55 to an intermediate point.

Signed at Winnipeg, this 3rd day of January, 1924.

ARNOLD LAING.

In the presence of—

GERALD S. ROXBURGH,
W. C. BOGESS.
